Attorney

UNITED STATES PATENT OFFICE.

WILLIAM N. METCALF, OF DE WITT, ARKANSAS.

CRANK-SHAFT-DRESSING IMPLEMENT.

Application filed May 8, 1923. Serial No. 637,538.

To all whom it may concern:

Be it known that I, WILLIAM N. METCALF, a citizen of the United States, residing at De Witt, in the county of Arkansas and 5 State of Arkansas, have invented certain new and useful Improvements in Crank-Shaft-Dressing Implements, of which the following is a specification.

This invention relates to crank shaft dressing implements and has for an object to 10 provide a manually operated device of simple construction which will dress down a crank shaft or the like while in position upon the regular installation and insure accuracy 15 of dressing.

A further object of the invention is to provide a crank shaft dressing implement comprising spaced and adjustable cutting tools analogizing files, with means for reciprocating the device as an entirety for the 20 purpose of actuating the cutters while rotating the shaft, to insure circular accuracy.

With these and other objects in view, the 25 invention comprises certain novel parts, elements, units, combinations, interactions and functions as disclosed in the drawings, together with mechanical equivalents thereof, as will be hereinafter more fully described and claimed.

30 In the drawings:

Figure 1 is a view of the device in perspective in operative position upon a crank shaft.

Figure 2 is a view of the device in side 35 elevation, showing the relative rotation of the implement relative to the shaft for dressing purposes.

Like characters of reference indicate corresponding parts throughout the several 40 views.

It is well known that in the operation of various mechanical devices employing shafts and, more especially, crank shafts said shafts become worn to depart from true circularity. 45 It is desirable to dress down the shaft to return the shaft to circular condition, to insure smooth running of the parts. It is often-times impractical to remove the shaft from the installation and insert it in a lathe or 50 other mechanical device for dressing down

the flat part; also an expensive operation. The present device, intended to overcome these drawbacks, comprises a pair of bars, 10 and 11, spaced apart by means of adjusting the bolts, 12, having nuts, 13 and 14, for 55 adjusting the spacing of the bars, 10 and 11.

Upon the proximate surfaces of the bars, 10 and 11, cutting implements, 15 and 16, are secured such cutting implements preferably analogizing files and removably secured 60 thereto by some appropriate mechanical means, as the clamps, 17.

At opposite ends, the bars 10 and 11 are provided with appropriate hand-holds, 18 and 19, respectively, so that the operator 65 may grasp either one or both of these hand-holds for actuating the device. In operation, the bars 10 and 11 and their cutters, 15 and 16, are separated by removing the nuts, 14, and are placed upon the shaft, 20, which 70 is to be dressed down. The device as an entirety is then reciprocated throughout all or a portion of the effective length of the cutters, 15 and 16, and simultaneously turned or, as convenience may make desirable, the 75 shaft is turned relative to the reciprocating plane of the organization. By adjusting the parts so that the cutters, 15 and 16, shall be spaced accurately relative to the smallest diameter of the shaft as indicated at Figure 80

2 and by such continued reciprocation and turning, the parts of greater diameter will be dressed down to correspond to the parts of lesser diameter, producing a cylindrical effect. This may be easily and readily accomplished while the shaft is still in situ and at a great saving in expense over removing 85 the shaft from the organization and turning or otherwise dressing.

I claim:

A shaft dressing implement comprising side bars, means to adjust the relation of the bars in parallelism, spaced clamps slideable upon the bars, and cutters having their opposite ends engaged by the clamps and 95 clamped rigidly thereby relative to the side bars.

In testimony whereof I affix my signature.

WILLIAM N. METCALF.
